UNITED STATES PATENT OFFICE.

EDWARD H. WEATHERHEAD, OF CLEVELAND, OHIO.

DESIGN FOR AN AIR-COMPRESSOR CASE.

SPECIFICATION forming part of Design No. 19,765, dated April 15, 1890.

Application filed February 8, 1890. Serial No. 339,741. Term of patent 14 years.

To all whom it may concern:

Be it known that I, EDWARD H. WEATHERHEAD, a citizen of the United States, residing at Cleveland, in the State of Ohio, have invented and produced a new and original Design for a Case for Hydraulic Air-Compressors, of which the following is a specification.

The drawing represents a vertical elevation of a hydraulic air-compressor case in accordance with my design.

The leading feature of my design is a hydraulic air-compressor case having a cylin-

drical body A, a rounded top a, and a standard A', supporting the body and cap. The air-compressor case presents the design. 15

I claim—

The design for a hydraulic air-compressor case herein shown and described, comprising the standard A', a cylindrical body A, and the rounded cap a, substantially as set forth. 20

EDWARD H. WEATHERHEAD.
